(57) **CLAIM**

I claim the ornamental design for a deer repeller, as shown and described.

DESCRIPTION

FIG. 1 is a front right bottom perspective view of the new ornamental deer repeller of the present invention;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken line showing of environment in the drawings is included for the purpose of illustrating only and forms no part of the claimed design.
